UNITED STATES PATENT OFFICE

142,284

DESIGN FOR A DESK ORNAMENT

Martin Cody Keating, Burbank, Calif.

Application February 20, 1945, Serial No. 118,052

Term of patent 7 years

(Cl. D74—1)

To all whom it may concern:

Be it known that I, Martin C. Keating, a citizen of the United States, residing in the city of Burbank, county of Los Angeles, and State of California, have invented a new, original, and ornamental Design for a Desk Ornament, of which the following is a specification, reference being had to the accompanying drawing, forming a part thereof.

The single figure is a top perspective view of the desk ornament showing my new design.

I claim:

The ornamental design for a desk ornament, as shown.

MARTIN CODY KEATING.
